UNITED STATES PATENT OFFICE.

ROY M. MESSICK, OF WASHINGTON, DISTRICT OF COLUMBIA.

CHECK-DELIVERING DEVICE.

1,186,113.

Specification of Letters Patent. Patented June 6, 1916.

Application filed January 21, 1916. Serial No. 73,410.

To all whom it may concern:

Be it known that I, ROY M. MESSICK, a citizen of the United States, residing at Washington, in the District of Columbia, ⁵ have invented new and useful Improvements in Check-Delivering Devices, of which the following is a specification.

This invention relates to a distributor, and more particularly to the class of automatic check or coin delivering devices. ¹⁰

The primary object of the invention is the provision of a device of this character wherein a plurality of checks or coins are securely held so that it is impossible to tamper ¹⁵ with or extract a check or coin therefrom without sounding an alarm, thereby eliminating all possibility of theft, the checks being singly ejected on operating the device, thereby enabling the same to be used in ²⁰ various lines of business where checks or coins having an individual valuation are given out for time or piece-work.

Another object of the invention is the provision of a device of this character ²⁵ wherein, on ejecting each check or coin, a register is automatically actuated so that it can be readily determined with accuracy the exact number of checks or coins given out at any particular time, thereby indicating ³⁰ the time consumed by the laborer in perfecting work or the quantity of piece-work performed.

A further object of the invention is the provision of a device of this character ³⁵ wherein, should the operator of the same be temporarily absent, the device can be locked, which prevents any one tampering with it and extracting the checks or coins therefrom.

⁴⁰ A further object of the invention is the provision of a device of this character which is extremely simple in construction, designed particularly for use in fruit or vegetable canning factories for the distribution of ⁴⁵ time or piece-work checks adapted to be given out to laborers such as fruit or vegetable peelers, and also one which is thoroughly reliable and efficient in its operation and inexpensive in manufacture.

⁵⁰ Other objects will be in part obvious and in part hereinafter pointed out.

The invention accordingly consists in the features of construction, combination of elements and arrangement of parts which will ⁵⁵ be exemplified in the construction herein-after described, and the scope of the appli-

cation of which will be indicated in the appended claim.

In the accompanying drawings: Figure 1 is a side elevation of a device constructed in accordance with the invention; Fig. 2 is a similar view looking toward the opposite side thereof; Fig. 3 is a fragmentary vertical longitudinal sectional view; Fig. 4 is a sectional view on the line 4-4 of Fig. 1; ⁶⁰ Fig. 5 is a top plan view; Fig. 6 is a sectional view on the line 6-6 of Fig. 5.

Similar reference characters designate corresponding parts throughout the several views of the drawing. ⁷⁰

Referring to the drawing in detail, the distributor or device comprises a tubular body or column 10 which forms a check or coin container or chute, and is provided in its front with several longitudinally disposed rows of spaced openings 11 so that inspection can be had to determine the number of checks or coins therein or the height of the same interiorly of the body or column. Secured to the back of the body or column ⁷⁵ 10 are spaced hanger plates 12, each being formed with a keyhole shaped slot 13 for receiving a screw or other like fastener for the detachable mounting of the body or column 10 upon a support or wall of an ⁸⁰ enclosure.

Arranged at the lower end of the body or column 10 is a check or coin conductor, comprising superimposed horizontally disposed plates 14 and 15, the same being securely fastened to each other, the plate 14 being formed with a hollow boss 16 in which is secured the lower end of the body or column 10, while the lower plate 15 is provided with a central longitudinally disposed guideway ⁹⁵ 17 in which is arranged an ejector slide 18 which, near its inner end, is formed with a circular opening 19 adapted to normally register with the bore of the body or column 10 for receiving a check or coin therefrom ¹⁰⁰ into the opening 19 so that the said check or coin can be advanced on pulling outwardly upon the slide 18 to bring it into registration with a discharge opening 20 formed in the bottom plate 15, and in this manner the coin or check is delivered.

The ejector slide 18 at its front end is formed with a depending lip which permits the pulling of the said slide outwardly in the guideway 17, while the rear end of the ¹¹⁰ said slide is extended beyond the plates 14 and 15 and is provided with a downturned

shallow flange 22, which serves to operate a signal on movement of the said slide in a manner presently described.

The signal comprises a bell 23 which is mounted upon a stem 24, the same depending from a base plate 25 which is suitably secured to the plate 15, and this base plate 25 is formed with a lateral extension 26 to which is pivoted at 27 a resilient trip arm 28 having at its free end an upturned nose 29 which is passed through a suitable slot 30 in the base plate 25 to project into the path of movement of the flange 22 to be operated thereby for the swinging and automatic tripping of the said arm 28 which carries a bell clapper 31 adapted to strike the bell 23 for the sounding thereof.

Connected to the arm 28 is a coiled retractile spring 32 which is also connected to the extension 26 of the base plate 25 so as to automatically move the arm to bring the clapper 31 into engagement with the bell 23 for the sounding thereof when the trip arm 28 has been automatically moved by the slide 18 and tripped thereby when the flange 22 rides over the nose 29 on the arm 28, and in this manner the bell is automatically sounded.

Connected to the front end of the slide 18 is one end of a retractile spring 33 which is also connected to the plate 15 near the rear end thereof, and this spring is designed to automatically move the slide inwardly or rearwardly after being pulled outwardly, and during the rearward or inward movement of the slide the flange 22 thereof will ride over the nose 29 on the trip arm 28 so that when the slide is again pulled outwardly the bell will be automatically sounded.

40 Mounted upon the top plate 14 of the ejector is a register 34, the actuating arm 35 of which is connected with a lever 36 which is pivoted to the front end of the slide 18 so that on pulling outwardly upon the latter 45 the register 34 will indicate each time a check or coin is ejected from the device. Formed on the plate 14 at opposite sides of the actuating arm 35 of the register 34 are stop pins 37 which limit the swinging action 50 of the arm while the lever 36 is slotted at 38 to receive the connections with the arm 35 and thereby permit the proper movement of the slide and the actuation of the register when said slide is pulled outwardly for the 55 ejecting of a check or coin from the device.

Formed in the body or column 10 spaced from the upper open end thereof are diametrically opposed slots 39 in which is movably fitted a closure hasp 40 provided 60 with an aperture 41 for the fastening of a

lock 42 thereto so that the closure hasp 40 cannot be removed from the body or column 10 until the lock is detached therefrom, the body or column 10 being filled with checks or coins through the upper open end thereof 65 when the hasp 40 has been detached or removed therefrom.

Formed in the plates 14 and 15 and in the slot 18 are vertically registering holes or openings 43 which permit the insertion of 70 a suitable lock for the fastening of the slide 18 against movement so that in event of the operator of the machine being temporarily absent it will be impossible to actuate the machine, thereby preventing any one from 75 tampering with the same and extracting the checks or coins therefrom.

From the foregoing description, taken in connection with the accompanying drawings, the construction and manner of operation of my check or coin delivery device will be readily apparent and, therefore, a more extended explanation has been omitted.

Having thus described my invention, I claim:

A device of the class described comprising a tubi-form column forming a check container having a plurality of rows of spaced openings longitudinally therein and constituting peep holes, a pair of superimposed plates, the uppermost plate being formed with an opening registering with the bore in the column, a flange concentrically about the last named opening and receiving the lower end of said column, the lowermost plate being formed with a longitudinal guideway opening through both ends thereof, an ejector slide movable in said guideway and having an opening for registration with the opening in the uppermost plate, a pull lip 100 formed on one end of the slide, said lowermost plate being formed with an opening with which is adapted to register the opening in the slide when moved in one direction, a register mounted on the uppermost plate 105 and having an operating arm, a lever pivoted to the pull lip and loosely connected with the operating arm for actuating the same on movement of the slide, an audible signal connected with the lowermost plate, and means on the opposite end of the slide for actuating the signal upon movement of said slide.

In testimony whereof I affix my signature in presence of two witnesses.

ROY M. MESSICK.
